UNITED STATES PATENT OFFICE.

CHARLES M. WIBLE, OF MOUNT PLEASANT, PENNSYLVANIA.

DESIGN FOR A HEADLIGHT-LENS.

54,158.

Specification for Design.

Patented Nov. 4, 1919.

Application filed July 5, 1919. Serial No. 308,909. Term of patent 7 years.

To all whom it may concern:

Be it known that I, CHARLES M. WIBLE, a citizen of the United States, residing at Mount Pleasant, in the county of Westmoreland and State of Pennsylvania, have invented a new, original, and ornamental Design for a Headlight-Lens, of which the following is a specification.

In the accompanying drawing,
Figure 1 is a front plan view and

Fig. 2 is an edge view of the headlight lens.

I claim:

The ornamental design for a headlight lens as shown.

CHARLES M. WIBLE.

Witnesses:

WALTER S. WIBLE,
R. C. MARTZ.
